UNITED STATES PATENT OFFICE.

EARL W. HOWE, OF NORFOLK, VIRGINIA.

LETTER-OUTLINER.

1,331,262.

Specification of Letters Patent.

Patented Feb. 17, 1920.

Application filed September 20, 1919. Serial No. 325,199.

To all whom it may concern:

Be it known that I, EARL W. HOWE, a citizen of the United States, residing at Norfolk, in the county of Norfolk, State of Virginia, have invented a new and useful Letter-Outliner; and I do hereby declare the following to be a full, clear, and exact description of the invention, such as will enable others skilled in the art to which it applies to make and use the same.

The invention relates to letter outliners and has for its object to provide a letter outliner so that those not skilled in lettering may form the outline of various letters quickly, after which the letters may be filled in easily and quickly by one unskilled in lettering.

A further object is to construct a letter outliner from a single piece of sheet metal 20 rectangular in shape and to provide the outline of a letter formed from a series of apertures, said apertures being adapted to have a piece of material, such as cord, tape or the like rove through the apertures for the reception of a marking fluid or material so that the outline of a letter may be impressed or stamped in any place desired.

A further object is to provide a letter outliner comprising a body member preferably 30 rectangular in shape and having integral lugs bent inwardly on its rear face for the reception of lugs carried by a handle, the handle comprising right angle arched members arching each other, one of said arched members being bent centrally so as to form a lug for engaging the central portion of the body member thereby forming means for applying pressure centrally of the body member simultaneously with the application 40 of pressure to the marginal edges of the body member so as to get a uniform impression. The arched members forming the handle being preferably formed of spring material so that the lugs thereof may be sprung 45 into and out of engagement with the lugs carried by the rear face of the body member, thereby allowing the same handle member to be applied to various body members having various letters or designs thereon.

With the above and other objects in view the invention resides in the combination and arrangement of parts as hereinafter set forth, shown in the drawings, described and claimed, it being understood that changes in 55 the precise embodiment of the invention may be made within the scope of what is

claimed without departing from the spirit of the invention.

In the drawings:

Figure 1 is a perspective view of the letter outliner showing the detachable handle applied thereto.

Fig. 2 is a front view of the letter outliner.

Fig. 3 is a sectional view taken on line 65 3-3 of Fig. 2.

Fig. 4 is a detail perspective view of a portion of the body member showing the method of weaving an ink or other marking material string through the apertures.

Fig. 5 is a detail perspective view of a portion of the body member showing another method of weaving a marking tape through elongated apertures which is particularly adapted for large letters of the 75 type used on signs and the like.

Referring to the drawings, the numeral 1 designates a metallic body member and 2 a series of L-shaped lugs carried at opposite sides of the body member and overlying the 80 rear face of the body member, thereby forming recesses 3 for the reception of the lugs 4 carried by the arched members 5 which form a handle for the body member. One of the arched members 5 is bent as at 6 and 7 so as 85 to form downwardly extending members 8 there being a bend 9 so as to form a downwardly extending lug 10 adapted to engage the rear face of the body member 1. When the body member 1 is placed on an object on 90 which a letter is desired to be outlined and pressure is applied to the handle member, lugs 4 will impart a pressure to the marginal edges of the body member and the lug 10 will impart a pressure on the central portion 95 of said body member, thereby insuring a uniform impression of the design on the article on which it is being stamped. Arched members 5 are secured together as at 11 so that they will be maintained in 100 proper relation to each other. The arched members 5 are preferably made of spring material so that they may be sprung into and out of engagement with the recesses 3 formed by the lugs 2, thereby allowing the 105 same handle member to be used on various body members on which different designs, letters or numerals are shown.

Letters, designs or figures are formed in the body member by a series of apertures 12, 110 that is the outlines of said letters, figures or designs, however for the purpose of illustra-

tion a letter is formed. When it is desired to outline a letter so that the same may be stamped on an article or material a flexible strip 13 is rove through the various apertures 12. Strip 13 is preferably made of a material which will hold a marking ink, powder or the like, so that when the body member is forced downwardly for making the outline on an article said outline will be left thereon in ink, powder, or if so desired the impression of the strip 13. This operation is repeated with several body members having various letters or designs, however the same handle member is applied to the various body members. The letters on the various body members are so spaced so that it will only be necessary to register the side edge of each body member with the edge of the letter already outlined to get the proper spacing for the letters.

Referring to Fig. 5 the body member 1 is provided with a series of elongated apertures 12^a through which loops 14 of a wide pliable tape 15 are passed, said loops being adapted to have passed therethrough a series of pins 16 so that the tape 15 will be maintained in position. This particular form is particularly adapted for extremely large letters. However, it is to be understood that tapes 13 and 15 may be rove through the various apertures in any way desired.

From the above it will be seen that a letter outliner is provided, by means of which the letters forming a sign may be quickly outlined by those unskilled in lettering. Also that an unskilled person may, after having outlined the letters, easily and quickly fill them in without having the necessary skill requisite to sign painting and lettering.

The invention having been set forth what is claimed as new and useful is:—

1. An outliner for letters comprising a body member, said body member being provided with an outline adapted to be impressed upon an article, said body member having marginal recesses for the reception of lugs carried by a handle member, said handle member being formed of spring material so that the lugs carried thereby may be sprung inwardly and may be allowed to spring outwardly for removing or placing the handle member on the body member.

2. A letter and design outliner comprising a body member, said body member being provided with an outline adapted to be impressed upon an article, said body member having marginal recesses for the reception

of lugs carried by a handle member formed of spring material, thereby allowing the lugs to be sprung inwardly and outwardly for removing or placing the handle member on the body member, and a downwardly extending lug carried by the handle member and substantially centrally disposed, said last named lug forming means whereby pressure will be imparted to the body member simultaneously with the application of pressure to the marginal edges of the body member during an outlining operation.

3. An outliner for letters comprising a body member, said body member being provided with an outline formed from a pliable strip rove through apertures therein, said body member being preferably rectangular in shape and provided with integral lugs at its opposite parallel sides thereby forming recesses, a handle member formed from a pair of arched members, lugs at the ends of the arched members adapted to be received by the recesses at the marginal edges of the body member, said arched members being secured together and formed of spring material so that the lugs thereof may be sprung into and out of engagement with the recesses of the marginal edge of the body member, one of said arched members being bent so as to form a downwardly extending lug adapted to engage the rear face of the body member substantially centrally thereof thereby forming means for applying a pressure substantially centrally of the body member simultaneously with the application of pressure along the marginal edges of the body member during a stamping operation.

4. An outliner for letters, figures, designs and the like formed in a body member and comprising a series of apertures and a pliable strip rove through said apertures and adapted to be impressed on an article for stamping the letter, figure or design on said article.

5. An outliner for letters, figures, designs and the like comprising a body member having a series of elongated apertures therein, said apertures being adapted to receive loops in a pliable impression strip, said loops being disposed on the opposite face of the body member, and transversely disposed pins passing through said loops for maintaining the pliable impression strip in position on the opposite face of the body member.

In testimony whereof I have signed my name to this specification.

EARL W. HOWE.
